(57) **CLAIM**

The ornamental design for a combined maternity abdominal and lumbar support, as shown.

DESCRIPTION

FIG. 1 is a right side/front perspective view of my new design for a combined maternity abdominal and lumbar support. The left side view is a mirror image of the right side. FIG. 2 is a front perspective view of the combined maternity abdominal and lumbar support.

FIG. 3 is an exploded rear perspective view of both components of the combined maternity abdominal and lumbar support, showing the inside or wearer side of the front panel; and,

FIG. 4 is an exploded front perspective of both components of the combined maternity abdominal and lumbar support, showing the inside or wearer side of the back panel.

Top and bottom views are omitted as they are flat and unornamented.

The partial outline of the pregnant physique, shown in broken lines in FIGS. 1 and 2, is for illustrative purposes only and forms no part of the claimed design.
